UNITED STATES PATENT OFFICE.

NICHOLAS SIMON, OF NEENAH, WISCONSIN.

DESIGN FOR A CHEESE.

SPECIFICATION forming part of Design No. 34,052, dated February 5, 1901.

Application filed January 10, 1901. Serial No. 42,808. Term of patent 7 years.

To all whom it may concern:

Be it known that I, NICHOLAS SIMON, a citizen of the United States, residing at Neenah, in the county of Winnebago and State of Wisconsin, have invented and produced a new and original Design for a Cheese, of which the following is a specification, reference being had to the accompanying drawings, forming part thereof.

1. Figure 1 is a perspective view of the upper or top side of a cheese and two of its edges, showing my new design. Fig. 2 is a perspective view of the reverse or bottom side and the other two edges, and Fig. 3 is a vertical section across the middle of Fig. 1 from left to right.

As shown in the drawings, the leading features of my design consist of a square cheese having a series of V-shaped grooves 1, which 2. divide the cheese into small rectangular sections, said V-grooves being arranged directly opposite each other upon opposite sides of the

cheese. They further consist of a series of half-circle grooves 2, arranged near the outer edges of each small rectangular section upon the top side of the cheese and forming thereby a series of smaller rectangular sections or name-plates for receiving any desired inscription.

The four edges of the cheese are plain and smooth.

Having thus described my said invention, what I claim as new, and desire to secure by Letters Patent, is—

The design for a cheese as herein shown and described.

In testimony whereof I have signed my name in the presence of two subscribing witnesses.

NICHOLAS SIMON.
